UNITED STATES PATENT OFFICE.

ADAM F. HOFF, OF BALTIMORE, MARYLAND.

ZONING MARKER FOR STREET TRAFFIC.

Application filed May 18, 1928. Serial No. 278,729.

This invention pertains to new and novel means for marking the streets and safety zones in certain localities where vehicle traffic is exceedingly heavy and dangerous.

5 The present custom of painting traffic lines to indicate center streets, cross walks on streets and street car zones, etc., has the disadvantage that the lines wear off and must be repainted constantly.

10 It has also been found that white, black, red and amber colors are the most suitable colors for markers to insure visibility, and it has been found that markers that have a surface even of a light alloy metal as brass, 15 copper or German silver do not bring the desirable results.

The object of my invention is to provide a street traffic marker that will be cheap to manufacture and will provide at the same 20 time the desirable coloring to insure visibility, and thus eliminate the painting of traffic lines.

Another object of my invention is to so construct my traffic marker that it will indicate 25 any desired coloring on the upper face of the marker, and that such color will be further permanently maintained by providing studs or projections on said upper face of the marker in such a manner that they will protect the recessed colored surfaces between the 30 studs or projections from wearing off while traffic moves on the upper surface of the marker, since the studs or projections will ward off any object that may travel on the 35 marker from getting in contact with the recessed colored surface so as to efface the coloring.

Another object of my invention is to add 40 additional durability and attractiveness to the upper surface of the marker by covering or coating the said upper face with baked enamel of any desired color, and to so arrange the studs or projections on its upper surface that it will protect the chipping off of the 45 enamel between the recesses when traffic moves over the upper surface of the marker.

Another object of my invention is to so 50 construct my marker that when it is desired to economize in the use of material of which the marker is composed that the bottom surface of the marker may be hollow and to provide integral reinforcements inside of the hollow surface.

Another object of the invention is to so 55 construct my improved marker that it may be readily installed within the street pavement

regardless of the material of which the street is constructed; that it will be always maintained permanently in the desired position; and that it may be disposed flush with the 60 surface of the street or slightly above the street surface.

The foregoing and such other objects as may appear from the ensuing description are attained by the construction, arrangement 65 and location of the parts hereinafter more fully described, illustrated in the accompanying drawings and more particularly pointed out in the claim appended hereto, it being understood that slight changes in the precise 70 form, proportions, and minor details of construction may be resorted to without departing from the spirit or sacrificing any of the advantages of the invention.

In the accompanying drawings forming a 75 part of this specification it will be seen that:

Figure 1 is a plan view of the improved means embodying my invention.

Figure 2 is a transverse section thereof taken in the plane of the dotted lines 2—2, 80 Fig. 1.

Figure 3 is a longitudinal section taken in the plane of the dotted lines 3—3, Fig. 1.

Figure 4 is a plan view of a slightly modified form. 85

Figure 5 is a section taken in the plane of the dotted lines 5—5, Fig. 4.

Figure 6 is a plan view of further modified form.

Figure 7 is a cross-section taken in the 90 plane of the dotted lines 7—7, Fig. 6, and

Figure 8 is a plan view of one other slightly modified form.

In the embodiment of my invention as illustrated it will be seen that the numeral 1 95 designates a zone marker, provided at its lowermost portion with a laterally extending flange 2, and formed with a central downwardly extended strengthening portion 3, a downwardly extended wall 4 formed at the 100 sides and ends thereof, while the inner portion thereof is hollow, the extended flange 2 serving to lock the marker within the street pavement, and in connection with the wall 4 to maintain said marker in its fixed and 105 permanent condition at all times and under all conditions.

The upper or top portion of the marker is formed of a portion 5, curved or arch-shaped from one side to the other, its upper face or surface being formed with a series of outwardly extended projections 6, and a series 110

of recesses or depressions 7 intervening between said projections, each of the said recesses or depressions being preferably curved or rounded at their ends and sides for the purpose of drawing off foreign material that may collect between the recesses and thus maintain the colored surface cleansed and visible as hereinafter described.

My improved marker is preferably coated or enameled over its upper face or surface with a suitable, easily visible coloring material, preferably baked enamel, and while the projecting surfaces will form a top surface of metal, rubber, or other composition over which traffic may travel, the recessed portions being out of contact with the heavy traffic will always maintain its readily visible color, under all conditions, and owing to the sloping sides and ends of the depressions or recesses, any dirt, dust, or other foreign material which may accumulate therein, is readily and easily cleaned out by the usual winds and rainfalls, thus always maintaining a readily visible color to indicate the safety zones and crossing lines to drivers of vehicles of all kinds, as well as to pedestrians.

It will be readily perceived that this particular type of marker may be formed of any suitable or desirable material possessing the required strength such as castings, pressed sheet metal or a composition to be embedded or installed within the material which constitutes the street pavement; that it may be coated or enameled with any suitable, readily visible coloring material, and that the marker may be formed of any suitable or desirable dimensions, contour, or letters, which may prove most desirable for the location and the purpose for which it is intended to be used, that is, for street crossings, safety zones, and side-walks.

By reference to Figs. 4 and 5 of the drawings it will be seen that a slightly modified form of structure or marker is shown, said structure or marker to be installed within the street pavement, and is provided with an outwardly extended flange 8 at its lower end, while its top wall 9 is provided upon its upper face with a series of projections 10 and 10', said projections being of different

heights with a curved depression 11 surrounding all of the said projections, said upper face being coated with a visible coloring 12.

It will be readily obvious that when a marker of the type hereinbefore referred to has been properly set or fixedly installed within the street pavement, it will serve as a permanent marker at all times, and will dispense with the expense of frequently painting the traffic lines and safety zones on the street pavements, which lines and zones are frequently invisible to the traffic.

Referring to Figs. 6, 7 and 8 of the drawings which disclose further slightly modified forms of the invention, the numeral 13 indicates a frame, having a removable cover 14 which is formed of any desirable material, said cover being provided with a series of slightly raised or projecting portions 15, and depressions 16, formed intermediate said projecting portions, said cover being secured in any suitable or desirable manner to said frame, said depression being coated or enameled with any suitable visible color, preferably white baked enamel or any other distinguishable coloring, and since the depressions are not subjected to wear by the heavy traffic, the marker will always be easily and readily visible.

It will be understood that the projecting surfaces may be suitably serrated or roughened to prevent accidental slipping during passage thereover.

Having thus described my invention what I claim and desire to secure by Letters Patent is:

In a device of the character described, a structure having its top surface curved along the longitudinal and transverse axes and provided over its entire surface with projections, the surface between same being coated with material to give same distinct visibility, the projections being of such height and so spaced as to prevent tires from scraping the coated surface and to act as a non-slipping surface, the curvature of the recessed surface being such as to permit free drainage and to prevent normally the collection of dirt.

ADAM F. HOFF.
